DRAG BUCKET

Werner Lehman, South Milwaukee, Wis., assignor
to Bucyrus-Erie Company, South Milwaukee,
Wis., a corporation of Delaware

Application June 6, 1932, Serial No. 615,534

18 Claims. (Cl. 37—135)

My invention relates to new and useful improvements in means for attaching the drag-chains to the drag buckets of dragline excavators.

Such buckets are well known in the art, one being

shown complete in my copending application, Serial No. 616,209 filed June 9, 1932. In such buckets it is customary to attach a drag-chain to the front edge of each side of the bucket, above and forward of the cutting edge; and in order to obtain the proper inclination of the cutting edge for digging in various types of material, it is customary to have the attaching means shiftable to two alternative points of attachment.

This might passably be accomplished by securing the two feet of a U-shaped clevis, by means of transverse bolts, to two plates (one inside and one out) projecting forwardly from the front edge of the bucket.

But I have found that this construction entails two difficulties: In the first place, the hammer back-and-forth of the clevis against its two retaining bolts causes wear and loosening on these bolts, and wear on the two plates. And, in the second place, there is great wear on the upper and lower front corners of the two plates. As the two plates are much more expensive than the clevis and bolts; and, because of their quasi-permanent attachment to the bucket itself, are much more difficult to replace; they should, if possible, be protected against such wear.

Accordingly it is the principal object of the present invention to provide such means for attaching the drag chains to drag buckets, as will eliminate the most of such wear.

In addition to my principal object, I have worked out a number of novel and useful details, which will be readily evident as the description progresses.

My invention consists in the novel parts, and in the combinations and arrangements thereof, which are defined in the appended claims; and of which one embodiment is exemplified in the accompanying drawing, which is hereinafter particularly described and explained.

Throughout the description, the same reference number is applied to the same member or to similar members.

Figure 1 is the side elevation of my invention assembled.

Figure 2 is the side elevation of one of the plates of my invention, taken along the line 2—2 of Figure 3.

Figure 3 is the bottom (i. e. edge) view of that plate, taken along the line 3—3 of Figure 2.

Figure 4 is the top view of the clevis of my invention, taken along the line 4—4 of Figure 5.

Figure 5 is the side elevation of that clevis, taken along the line 5—5 of Figure 4.

Figure 6 is the rear view of that clevis.

Figure 7 is a section of the filler of my invention, taken along the line 7—7 of Figure 8.

Figure 8 is the side elevation of that filler.

Referring to the drawing, it will be seen that 11 is the front lower portion of the left hand side of the casting forming the main body of a drag bucket. 12 is the outside one of a pair of identical clevis plates, having three bolt holes 13, 14, 15, and four rivet holes 16. This plate, and another identical to it, and occupying a similar position just within the wall of the bucket to that occupied by plate 12 just without the wall, are secured to the wall by rivets 17.

18 is my clevis. It has a chain attaching portion 19, two bolt holes 20, two sidewardly projecting guards 21, and two abutments 22. The purpose and importance of the abutments and guards will be discussed later herein.

23 is my filler. It has two sidewardly projecting guards 24, a bolt hole 25, and two portions 26, either of which can serve as an abutment.

Bolts 27 removably secure my clevis 18 and filler 23 to the plates 12.

When assembled, as in Figure 1, the abutments 22 of my clevis 18 abut against the front edge of the wall 11 of the bucket, thus assuring that the bolts 27 will be subjected only to pull and never to push. Guards 21 on my clevis 18, and guards 24 on my filler 23, are seen to protect the upper and lower corners 28 of my plates 12 from bumping and wear.

If I wish to increase the bite of the teeth of the bucket, I turn my clevis other-side-up, and secure it to holes 13 and 14; and secure my filler 23 to holes 15. The protection against thrust of the clevis, and against wear on the exposed corners of the plates, remains the same as before.

The construction on the other front side edge of the bucket is the same.

If desired, the chain-attaching portion 19 of 100 each clevis may be built with an inward bend, i. e. upward in Figure 4 for the left hand clevis, and downward for the right hand clevis, so that these chain-attaching portions of the two clevises will lie in the line of the converging drag chains. If this be done, then when the clevises are turned other-side-up and secured to holes 13 and 14, the two clevises will also have to interchange sides of the bucket.

Having now described and illustrated one form 110

of my invention, I wish it to be understood that my invention is not to be limited to the specific form or arrangement of parts hereinbefore described, except in so far as such limitations are 5 specified in the appended claims.

I claim:

1. In a drag-chain attachment for a drag bucket, the combination of: two plates adapted to be secured respectively to the inner and the outer 10 faces of the front of the side of the bucket, and to project forwardly beyond the front edge of the side of the bucket, and having at least three holes in the projecting part; a chain-attaching clevis, having abutments to bear against the front edge 15 of the side of the bucket, holes for bolting to the plates, and sidewardly projecting guards to protect the corners of the plates; a filler, having a hole for bolting to the plates, and sidewardly projecting guards to protect the corners of the plates; and means for attaching the clevis and the filler to the plates; the clevis being reversible and thus adapted to be secured either to the top or the bottom holes of the plates; and the filler being adapted to be secured to one of the remaining 20 holes of the plates.

2. In a drag-chain attachment for a drag bucket, the combination of: two plates adapted to be secured respectively to the inner and the outer faces of the front of the side of the bucket, 30 and to project forwardly beyond the front edge of the side of the bucket, and having at least three holes in the projecting part; a chain-attaching clevis, having means for attachment to the plates, and sidewardly projecting guards to protect the corners of the plates; a filler, having means for attachment to the plates; and sidewardly projecting guards to protect the corners of the plates; the clevis being reversible and thus adapted to be secured either to the top or the bottom 35 holes of the plates; and the filler being adapted to be secured to one of the remaining holes of the plates.

3. In a drag-chain attachment for a drag bucket, the combination of: two plates adapted 45 to be secured respectively to the inner and the outer faces of the front of the side of the bucket, and to project forwardly beyond the front edge of the side of the bucket, and having at least three holes in the projecting part; a chain-attaching 50 clevis, having abutments to bear against the front edge of the side of the bucket, holes for bolting to the plates, and sidewardly projecting guards to protect the corners of the plates; a filler, having a hole for bolting to the plates, and sidewardly 55 projecting guards to protect the corners of the plates; and means for attaching the clevis and the filler to the plates.

4. In a drag-chain attachment for a drag bucket, the combination of: two plates adapted 60 to be secured respectively to the inner and the outer faces of the front of the side of the bucket, and to project forwardly beyond the front edge of the side of the bucket, and having holes in the projecting part; a chain-attaching clevis, having 65 abutments to bear against the front edge of the side of the bucket, holes for bolting to the plates, and sidewardly projecting guards to protect the corners of the plates; and means for attaching the clevis to the plates.

70 5. In a drag-chain attachment for a drag bucket, the combination of: two plates adapted to be secured respectively to the inner and the outer faces of the front of the side of the bucket, and to project forwardly beyond the front edge 75 of the side of the bucket, and having holes in

the projecting part; a chain-attaching clevis, having abutments so proportioned and positioned that, in the normal assembled location of the clevis, they will constantly bear against the front edge of the side of the bucket, and holes for bolting to the plates; and means for attaching the clevis to the plates.

6. In a drag-bucket drag-chain-attaching assembly, the combination of: the bucket proper; two plates adapted to be secured respectively to the inner and the outer faces of the front of the side of the bucket proper, and to project forwardly beyond the front edge of the side of the bucket proper, and having three holes in the projecting part; a chain-attaching clevis, having means for attachment to the plates, and abutments to bear against the bucket proper or plates, and thus relieve the attaching means from thrust, and sidewardly projecting guards to protect the corners of the plates; and a filler, having means for attachment to the plates, and sidewardly projecting guards to protect the corners of the plates; the clevis being reversible and thus adapted to be secured either to the top or the bottom holes of the plates; and the filler being adapted to be secured to some of the remaining holes of the plates.

7. In a drag-chain attachment for a drag bucket, the combination of: two plates adapted to be secured respectively to the inner and the outer faces of the front of the side of the bucket, and to project forwardly beyond the front edge of the side of the bucket, and having holes in the projecting part; and a chain-attaching clevis, having means for attachment to the plates, and sidewardly projecting guards to protect the corners of the plates.

8. In a drag-bucket drag-chain-attaching assembly, the combination of: the bucket proper; two plates adapted to be secured respectively to the inner and the outer faces of the front of the side of the bucket, and to project forwardly beyond the front edge of the side of the bucket, and having three holes in the projecting part; a chain-attaching clevis, having means for attachment to the plates, and abutments to bear against the bucket proper or plates, and thus relieve the attaching means from thrust, and sidewardly projecting guards to protect the corners of the plates; and a filler, having means for attachment to the plates, and sidewardly projecting guards to protect the corners of the plates.

9. In a drag-bucket drag-chain-attaching assembly, the combination of: the bucket proper; two plates adapted to be secured respectively to the inner and the outer faces of the front of the side of the bucket, and to project forwardly beyond the front edge of the side of the bucket, and having holes in the projecting part; and a chain-attaching clevis, having means for attachment to the plates, and abutments to bear against the bucket proper or plates, and thus relieve the attaching means from thrust, and sidewardly projecting guards to protect the corners of the plates.

10. In a drag-bucket drag-chain-attaching assembly, the combination of: the bucket proper; two plates adapted to be secured respectively to the inner and the outer faces of the front of the side of the bucket, and to project forwardly beyond the front edge of the side of the bucket, and having holes in the projecting part; and a chain-attaching clevis, having means for attachment to the plates, and abutments to bear against the

bucket proper or plates, and thus relieve the attaching means from thrust.

11. In a drag-chain clevis for use in a drag-bucket drag-chain-attaching assembly, in which the drag-bucket comprises the bucket proper and two pairs of forwardly projecting chain-attaching plates, the combination of: a chain-attaching portion; portions for the reception of means for attachment to the bucket; abutments to bear against the bucket, and thus prevent thrust against the attaching means; and sidewardsly projecting guards, to protect the plates against wear; the clevis being open to admit the cooperating chain to the chain-attaching portion.

15. 12. In a drag-chain clevis for use in a drag-bucket drag-chain-attaching assembly, in which the drag-bucket comprises the bucket proper and two pairs of forwardly projecting chain-attaching plates, the combination of: a chain-attaching portion; portions for the reception of means for attachment to the bucket; abutments to bear against the bucket, and thus prevent thrust against the attaching means; and sidewardsly projecting guards, to protect the plates against wear.

13. In a drag-chain clevis for use in a drag-bucket drag-chain-attaching assembly, in which the drag-bucket comprises the bucket proper and two pairs of forwardly projecting chain-attaching plates, the combination of: a chain-attaching portion; portions for the reception of means for attachment to the bucket; and abutments so proportioned and positioned that, in the normal assembled location of the clevis, they will constantly bear against the bucket, and thus prevent thrust against the attaching means.

14. In a drag-chain clevis for use in a drag-bucket drag-chain-attaching assembly, in which the drag-bucket comprises the bucket proper and two pairs of forwardly projecting chain-attaching plates, the combination of: a chain-attaching portion; portions for the reception of means for attachment to the bucket; and sidewardsly projecting guards, to protect the plates against wear.

15. In a filler for use in a drag-bucket drag-chain-attaching assembly, in which the drag bucket comprises the bucket proper and two pairs of forwardly projecting chain-attaching plates, the combination of: a portion for the reception of means for attachment to the bucket; an abutment to bear against the bucket and thus prevent thrust against the attaching means; and sidewardsly projecting guards, to protect the plates against wear.

16. In a filler for use in a drag-bucket drag-chain-attaching assembly, in which the drag bucket comprises the bucket proper and two pairs of forwardly projecting chain-attaching plates, the combination of: a portion for the reception of means for attachment to the bucket; and sidewardsly projecting guards, to protect the plates against wear.

17. In a filler for use in a drag-bucket drag-chain-attaching assembly, in which the drag bucket comprises the bucket proper and two pairs of forwardly projecting chain-attaching plates, the combination of: a portion for the reception of means for attachment to the bucket; and an abutment so proportioned and positioned that, in the normal assembled location of the filler, it will constantly bear against the bucket, and thus prevent thrust against the attaching means.

18. In a filler for use in a drag-bucket drag-chain-attaching assembly, in which the drag bucket comprises the bucket proper and two pairs of forwardly projecting chain-attaching plates, the combination of: a portion for the reception of means for attachment to the bucket; abutments to bear selectively against the bucket, and thus prevent thrust against the attaching means; and sidewardsly projecting guards, to protect the plates against wear, the filler being selectively positionable, so that either one of the abutments can be used, and yet the guards will still perform their functions.
